(57) CLAIM

The ornamental design for a pants, as shown and described.

DESCRIPTION

FIG. 1 is a front, top, left side perspective view of a pants showing my new design;

FIG. 2 is a rear, top, left side perspective view, the rear, top, right side perspective view being the mirror image thereof; and,

FIG. 3 is an enlarged left side elevation view of the hip area, the enlarged right side elevation view of the hip area being the mirror image thereof.

1 Claim, 3 Drawing Sheets

FIG. 1

FIG. 3
